CLAIM

The ornamental design for an eye care massager, as shown and described.

DESCRIPTION

FIG. 1 is a perspective view of the eye care massager showing my new design;

FIG. 2 is a top plan view thereof;

FIG. 3 is a rear elevational view thereof;

FIG. 4 is a bottom plan view thereof;

FIG. 5 is a right side view thereof;

FIG. 6 is a front elevational view thereof; and,

FIG. 7 is a left side view thereof.
